UNITED STATES PATENT OFFICE.

JOHN F. GAIL, OF KENOSHA, WISCONSIN, ASSIGNOR TO THE SIMMONS MANUFACTURING COMPANY, OF SAME PLACE.

SPRING BED AND SEAT BOTTOM.

SPECIFICATION forming part of Letters Patent No. 639,222, dated December 19, 1899.

Application filed January 16, 1899. Serial No. 702,348. (No model.)

To all whom it may concern:

Be it known that I, JOHN F. GAIL, a citizen of the United States, residing at Kenosha, in the county of Kenosha and State of Wisconsin, have invented certain new and useful Improvements in Spring Bed and Seat Bottoms, (Case A;) and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 For convenience in making cross-reference this application is designated "Case A," and four other applications for Letters Patent for bed-bottoms executed by me of even date here-with are designated, respectively, "Case B," "Case C," "Case D," and "Case E."

This invention relates particularly to spring bed-bottoms formed of vertical spiral springs united horizontally by tie-rods.

The improvement involves the use of a new 25 form of tie-rod which permits the use of the simplest form of vertical spiral springs and which allows the ready assembling of the parts of the bed-bottom to constitute the finished structure. There is economy in the ready 30 assembling of these parts and there is also economy in the use of a simple form of the spiral spring.

My improvement results in a structure which has a high degree of strength, a distribution of strain applied at any particular 35 point, and an even surface.

In the accompanying drawings, Figure 1 is a plan of a portion of a bed-bottom embodying my improvement. Fig. 2 is a similar view 40 embodying a modification of the tie-rods and assemblage of the parts of the bed-bottom. Figs. 3, 4, 5, 6, 7, 8, and 9 illustrate other modifications.

Inasmuch as the general construction of 45 bed-bottoms of this class is well known I deem it sufficient to illustrate only portions of bed-bottoms showing the application of my improvement.

50 Referring first to Fig. 1, A is a rectangular frame forming the margins of the bed-bottom. This frame may be of wood or metal; but it

is preferably made of metal rods or bars somewhat heavier than the metal of the springs and tie-rods. B B are the springs. These are arranged in rows parallel to the sides of the frame A and are in vertical position and of spiral form, the upper end of each being formed into a complete ring B' by "knotting" or in any suitable manner. The spring may be cylindric in outline or it may be conical or double conical. As already stated, it is the object of the invention to embody the well-known forms of vertical bed-springs into a bed-bottom of superior quality and the parts of which may be readily made and readily assembled. C is a tie-rod extending transversely across the bed-bottom and having its ends suitably attached to the frame A and engaging two rows of springs B.

In Fig. 1 the tie-rods are shown extending above or over the rings B' of the springs of one transverse row and provided with V-shaped folds or loops C', extending through the ring of that spring and through the ring of the adjacent spring of the next transverse row, the loop being bent vertical, so as to extend through the last-mentioned ring out of the plane of the latter. The transverse rows of springs B adjoining the frame A are united to said frame by one of said tie-rods, 75 the loops C' extending partially around the said frame. Another set of tie-rods D D, which for convenience I will term "key-rods," are arranged at right angles to the tie-rods C. These are straight and extend centrally over 80 the longitudinal rows of springs B and beneath the vertical part C² of each loop C' in the row of springs traversed by said key-rod. The ends of the key-rod D may be suitably secured to the frame A, preferably in engagement with a loop C', engaging the frame at that point, the rod reaching through the loop. It will now be seen that the bed-bottom illustrated by said Fig. 1 consists of only four kinds of parts—namely, the frame A, springs B, tie-rods C, bearing the loops, and the straight key-rods D—and it will now be understood that the assembling of these parts to form the complete bed-bottom is a simple process involving only the use of the hands and a simple bending-tool for securing the ends of the tie-rods and key-rods. The frame may

be first put into position and the springs then placed in rows within the frame. The tie-rods B are then put into position with reference to the springs and the frame and the ends of said tie-rods bent around the frame or secured in any other suitable manner. The key-rods D are then successively put into position by passing them over the springs transversely to the tie-rods C and beneath the loops of the latter, the ends of said key-rods D being secured, as by bending around the frame or otherwise. This results in a very positive interconnection of the springs and the forming of such a surface as will not yield unduly at any one point, pressure at any point involving the depression of a considerable area of the bed-bottom surface. The fact is also to be noted that the key-rods D, extending midway over the rings B, prevent the central portion of the spring from pushing upward through the ring B', as is sometimes the case when the upper portion of the spring is left unprotected. The key-rods D may have upward bends d where they cross the rings B', as shown in Fig. 5, whereby recesses are formed to receive said rings.

The form of bed-bottom shown in Fig. 2 differs only from the form shown in Fig. 1 in that the tie-rods E, corresponding to the tie-rods C of Fig. 1, pass beneath the rings F' of the springs F, the springs F and the rings F' corresponding to the springs B and rings B', respectively, of Fig. 1, while the loops E' pass over instead of under the rings of the springs under which said tie-rods pass, and the marginal tie-rod E has its loops E' extending over instead of under the frame G, and they are bent nearly once around the frame, so as to again rise sufficiently to receive the key-rods H H.

The modification shown in Fig. 3 differs only from the form shown in Fig. 1 in that the loop C', after passing beneath the spring-ring upon which its tie-rod rests, passes over the ring of the adjacent spring, and its vertical part extends downward through the latter ring, and the key-rod D, after extending over the first ring, extends beneath the second.

In Fig. 4 the frame A is omitted. The ends of the tie-rods C are wound around the spring-rings or otherwise secured, and the loops C' of the outer tie-rod are bent around the spring-rings. On the two upper spring-rings at the left the tie-rod passes over the spring-ring and the loops pass downward through and then upward over the ring. On the spring at the left the loop comes first upward through the ring and then downward around it. The ends of the key-rods engage both the loop and the ring in the same manner that they engage the loop and frame in Figs. 1 and 2.

In Figs. 1, 2, 3, and 4 the loops are integral with the tie-rods. In Figs. 6, 7, 8, and 9 the loops are in position and engagement, as in Figs. 1, 3, and 4, but they are not integral

with the tie-rods. They are separate pieces suitably attached to the tie-rods and extending laterally to engage the two rows of springs, substantially as shown in Figs. 1, 3, and 4.

Figs. 6 and 7 illustrate the same construction, the former being a plan and the latter a vertical section. I is a spring, and I' is its ring. J is a transverse tie-rod extending over said ring, but having suitably-spaced upward bends J', which allow the main portion of the tie-rod to rest below the level of the ring I'. J² is a loop formed at its outer end like the loop shown in Figs. 1, 3, and 4, while its inner ends extend beneath the ring I', over the tie-rod J, and around the latter. The key-rod K passes over the ring I' and beneath the tie-rod J at the middle upward bend J' and beneath the loop J².

In the form shown in Figs. 8 and 9 the construction is like that shown in Figs. 6 and 7, excepting that the inner ends of the loop pass a second time beneath the ring of the spring and then around the tie-rods at the upward bends of the latter. In said Figs. 8 and 9 L is the ring of the spring. L' is the transverse tie-rod, having the three upward bends L², corresponding to the upward bends J' of Figs. 6 and 7. L³ is the loop, and M is the key-rod.

It will be seen on making a comparison of these several figures that there is in each variation of form a tie-rod having lateral loops extending through two spring-rings and around key-rods.

In all the forms the loop passes or enters the plane of the spring-ring only far enough to let the key-rod pass under strain.

It will be understood that my invention may be applied to spring-seats, and that the foregoing description is applicable to spring-seats as well as to spring bed-bottoms.

The construction illustrated by Fig. 2 is made the subject-matter of the application designated as "Case B," to which reference has been made. The forms illustrated by Figs. 6, 7, 8, and 9 are made the subject-matter of the application designated as "Case C," and the form illustrated by Figs. 8 and 9 is made the subject-matter of the application designated as "Case D." The form illustrated by Fig. 4, the same being a structure not having the marginal frame, is made the subject-matter of the application designated as "Case E."

I claim as my invention—

1. The combination of spiral springs arranged in rows and having the ends formed into rings, single, parallel tie-rods extending across said springs and bearing lateral loops extending through two adjacent springs, and key-rods arranged transversely to the said tie-rods and extending along said springs and through said loops, substantially as shown and described.

2. The combination of a rectangular frame, spiral springs arranged in rows and having their ends formed into rings, single, parallel tie-rods extending across said frame and

- 5 springs and bearing lateral loops extending through two adjacent springs, and key-rods arranged transversely to the said tie-rods and extending along said springs and through said loops, substantially as shown and described. 5. The combination of a rectangular frame, spiral springs arranged in rows and having their ends formed into rings, single, parallel tie-rods extending across said frame and 10 springs and bearing lateral loops extending through two adjacent springs, and key-rods arranged transversely to the said tie-rods and extending along said springs and through said loops and having their ends suitably attached 15 to said frame, substantially as shown and described. 6. The combination of a rectangular frame, spiral springs arranged in rows and having their ends formed into rings, single, parallel tie-rods extending across said frame and 20 springs and bearing lateral loops extending downward through the rings of one row of springs and laterally beneath and upward through the adjacent rings of the adjacent row of springs, and key-rods arranged transversely to said tie-rods and extending midway over rows of springs and beneath said loops where the latter rise through the spring-rings, substantially as shown and described. 7. The combination of a rectangular frame, spiral springs arranged in rows and having their ends formed into rings, single, parallel tie-rods extending across said frame and bearing lateral loops extending downward through the rings of one row of springs and laterally beneath and upward through the adjacent rings of the adjacent row of springs, and key-rods arranged transversely to the said tie-rods and extending midway over rows of springs and beneath said loops where the latter rise through the spring-rings and said key-rods having their ends suitably attached to said frame, substantially as shown and described. 8. The combination of a rectangular frame, spiral springs arranged in rows and having their ends formed into rings, single, parallel tie-rods extending across said frame and bearing lateral loops integral with said tie-rods and extending through two adjacent springs, and key-rods arranged transversely to the said tie-rods and extending over the said springs and through said loops, substantially as shown and described. 9. The combination of a rectangular frame, spiral springs arranged in rows and having their ends formed into rings, single, parallel tie-rods extending across the said frame and bearing lateral loops integral with said tie-rods and extending downward through the rings of one row of springs and laterally beneath and upward through the adjacent rings of an adjacent row of springs, and key-rods arranged transversely to said tie-rods and extending midway over rows of springs and beneath said loops where the latter rise through the spring-rings, substantially as shown and described. 10. The combination of a rectangular frame, spiral springs arranged in rows and having their ends formed into rings, single, parallel tie-rods extending across the said frame and bearing lateral loops integral with said tie-rods and extending downward through the rings of one row of springs and laterally beneath and upward through the adjacent rings of an adjacent row of springs, and key-rods arranged transversely to said tie-rods and extending midway over rows of springs and beneath said loops where the latter rise through the spring-rings and said key-rods having their ends suitably attached to said frame, substantially as shown and described. 11. The combination of a rectangular frame, spiral springs arranged in rows and having their ends formed into rings, single, parallel tie-rods extending across said frame and springs and bearing lateral loops extending through two adjacent springs, and one such tie-rod parallel to the others and having its loops extending through the rings of a marginal row of springs and around the adjacent portion of said rectangular frame, and key-rods arranged transversely to the said tie-rods and extending along said springs and through said loops, substantially as shown and described. 12. The combination of a rectangular frame, spiral springs arranged in rows and having their ends formed into rings, single, parallel tie-rods extending across said frame and springs and bearing lateral loops extending through two adjacent springs, and one such tie-rod parallel to the others and having its loops extending through the rings of a marginal row of springs and around the adjacent portion of said rectangular frame, and key-rods arranged transversely to the said tie-rods and extending along said springs and through said loops and around the sides of said frame, substantially as shown and described. 13. The combination of a rectangular frame,

4

1 spiral springs arranged in rows and having their ends formed into rings, single, parallel tie- rods extending across said frame and springs and bearing lateral loops extending 5 downward through the rings of one row of springs and laterally beneath and upward through the adjacent rings of the adjacent row of springs, another such tie-rod parallel to the others and having its loops extending 10 downward through the rings of a marginal row of said springs and thence beneath and upward around the adjacent portion of said frame, and key-rods arranged transversely to the said tie-rods and extending midway 15 along rows of springs and beneath said loops where the latter rise through the springs and around said frame, substantially as shown and described.

14. The combination of a rectangular frame, 20 spiral springs arranged in rows and having their ends formed into rings, single, parallel tie-rods extending across said frame and bearing lateral loops integral with said tie-rods and extending through two adjacent springs,

and such a tie-rod parallel to the others having such loops integral therewith and extending through the rings of a row of said springs and around the adjacent portion of said frame, and key-rods arranged transversely to said tie-rods and extending over said springs and 30 through said loops, substantially as shown and described.

15. The combination of spiral springs arranged in rows and having their ends formed into rings, single, parallel tie-rods extending 35 across said springs and bearing lateral loops extending through two adjacent springs, and key-rods having bends, *d*, and arranged transversely to the said tie-rods and extending over said springs and through said loops, substantially as shown and described.

In testimony whereof I affix my signature in presence of two witnesses.

JOHN F. GAIL.
